(54) **STEAM, GENERATING**

(76) Inventor: **William Scarbrough**

William Scarbrough, Savannah, Georgia
Letter Patent

The subscriber refers to in these Letters Patent and the following part of the same containing a description in the words of the said William Scarbrough himself of his Improvement in the generation of Steam in the boiler of Steam Engines &c.

In accordance with these presents shall come, Be it known, that I William Scarbrough of the City of Savannah in the County of Chatham State of Georgia have made several useful improvements in the generation of steam in the boiler of Steam Engines &c and that the following is a full and exact description thereof.

I suppose or make as a fact, that the purpose of the heat already generated within a boiler is equal in degree upon the surface of the water, from which fresh steam is to be generated, to that on the parts of the boiler other than the surface of the water. It is my experiment, that in proportion to the extent of this purpose the particles of the water are compacted together; and that in proportion to this compaction is the efficiency of obtaining combustion or extraction for the boiler or heat to the various particles or molecules of this water which are to furnish the required vapor or steam. That this is a fact I have, to the evidence of the influence of the pressure of the atmosphere on water which has to undergo combustion. At York I find the boiling point of water to be 140°, 212 degrees of the thermometer. At Mexico to consequence of its much higher elevation, I find a very material reduction in the temperature of the boiling point & when the vapor of the water there is nearly entirely removed it will not boil in water we find the boiling point there, has materially reduced. But this is yet another & stronger illustration of the fact in point. When the experiments were first made at the dry dock of Naval Hospital for producing combustion in a separate boiler by the introduction of steam into the liquid in it from a detached boiler, it generates every attempt to produce the desired effect, rather with the steam to be carried off than to be applied to the bottom of the liquid. Why was this? Because the steam & water disposed of escape from a compacted the particles or molecules of the liquid together & it could be conjectured from the description or evidence for the boiler or

heat it contained. But the Steam flows down to the bottom. Contact heat is given in a different manner for the liquid forms a room for expansion above and the expansion permitted the easier introduction of the Caloric and consequently the disintegration of the particles or molecules from each other. & Now what is this disintegration? Does it not at once stamp the whole theory of absorption and desorption? The fact is most clearly elucidated and illustrated by the simple act of holding before a fire a wet towel or Napkin. The heat from the fire heat scarcely reaches it before we perceive the vapor or steam flying off from it.

Is it not as much steam or steam as if it arose from boiling water? And if so how came it that a temperature so long, much below the boiling point - so instantaneously produced a similar effect? This is to me as not the disintegration of the particles or molecules of the water from each other caused by the absorption of the minute vegetable fibers of which the towel or Napkin was composed? If this is true we then have again in mind the same towel or Napkin and drying out the water is dried inside these particles or molecules are reunited or re-integrated and the temperature of the boiling point has to be attained before the water will steam off its vapor or steam. The same fact is exemplified by water placed in an unglazed Clay Pigeon. The minute pores of the Clay disintegrate the particles or molecules of the water & they are all at the outside fly off more or less rapidly according to the prevalent temperature it may be the vapors from the towel or napkin to make room for themselves. The towel itself performs the same operation on a enlarged scale. These facts have here been noticed in order to fully illustrate upon the subject to elucidate the best importance of this disintegration in aiding the vapor the generation of steam. We will now proceed to state certain means for producing this disintegration within steam boilers.

It is known that the Caloric or heat especially for instance, that which is in the ordinary way is first transmitted to the rest of the fluid by that part of it next in contact with the fire or heat and that it but gradually makes its way toward the center. So if it is this difficulty it is proposed to have but as much as pipes of this Caloric through the medium of small horizontal vertical or diagonal pipes or pipes at once to the center, which will have the effect of insulating the surrounding or comprising against the same but heat and cool

or of the fluid in consequence of the greater expansion of the part of it nearest the Contact with the Calorie. But the tubes to accomplish the desired object requires, the space in the boiler will permit it. Hollow cones are to be placed with their side bases resting as near as possible to admit the circulation of the water below in that part of the boiler under which the flame passes, and their apices or apertures 2.34 or more inches above the level of the water in the Boiler.

It appears thereby followed will be to remove the heated water from below and to get it from the apex of the Cone in the same manner as lava from a crater of a Volcano or Calor water from a break form cone. These pipes or cones are not designed to be fixed in the boiler but are merely placed in them and can at pleasure be taken out & put in & removed as whole or in part. — and not at all unlikely, the proposed invention will mitigate may be efficiently aided by placing a baffle below the apex of each cone a sort of Catherdral with long small apertures through which the ejected hot water may be caused to percolate through these tiny small apertures while by the distinguished buck will have the effect greatly to accelerate the conversion of these particles into steam or vapour notwithstanding the preceding view that the temperature of steam can be no higher than that of the water from which it has been generated, for the latter still retains the latent heat which the former gave up on becoming vapour. The next object is to overcome the compaction of the particles or molecules of the water in the boiler by the pressure of the already generated steam upon it. The remedy for this has in these cases been already anticipated by that has been said of the difficulty experienced in carrying out the principles suggested of preventing condensation by steam from another boiler the effect.

If the steam generated in an adjacent boiler can be made to cover the desired surface by flowing the steam to the bottom of the fluid in the other boiler by should not the steam already generated in this steam last boiler if thrown in the same manner below the water by means of pipes connected with the steam, & even in a chamber produce an exactly similar effect. For by this open in the steam thus thrown to the bottom and placed directly in contact with the Calorie would by its increasing expanding the same readily ionize itself into water through the decomposition rate and thereby accelerate the generation of fresh steam. But although it may not be

claimed especially for obtaining the mixed Dis-integration. Still it is to be considered that atmospheric air either cold or hot (perhaps the former in preference on account of its greater density and capacity for expansion) might be forced to the middle or bottom of the water from which the Steam is generating and its expansibility might naturally assist in the proposed dis-integration and at the same time support an increased force to the Steam, & yet whilst its easier Condensation would materially reduce the labor of the air-pump of a low Pressure & Condensing Engine. The principle above set forth it will be manifest may be applied to boilers of almost every description whether vertically, horizontally, or otherwise placed; or whether they be of high or of low pressure and the one segment, rapid generation of the Steam ought in course to cause a material reduction in the Consumption of fuel.

What I claim as my new invention and not previously known in the above described Steam-boilers for generating Steam of high or low pressure; is the principle of transmitting the Calore through the Medium of small horizontal, vertical or diagonal pipes or tubes at once to the Boiler or other part of the fluid which will have the effect of preventing the compacting or compressing against the more contractive and cold parts of the said fluid in consequence of the greater expansion of that part of it nearest the contact with the Calore.

Also raising the water from below and discharging the same through the upper of the Cane or through the pipes or tubes above the base of the tubes in the boiler as above specified and described. There may be many methods for obtaining the same effect but I claim the principle as set forth in my Specification, however performed. Washington City, D. C. March 18, 1888
